UNITED STATES PATENT OFFICE.

OTTO SCHUTZ, OF NEW YORK, N. Y.

VALVE FOR PNEUMATIC TIRES.

1,211,245.

Specification of Letters Patent. Patented Jan. 2, 1917.

Original application filed October 6, 1914, Serial No. 865,268. Divided and this application filed July 1, 1916. Serial No. 107,028.

To all whom it may concern:

Be it known that I, OTTO SCHUTZ, a citizen of the United States, residing at New York, in the county of New York and State of New York, have invented new and useful Improvements in Valves for Pneumatic Tires, of which the following is a specification.

This application is a division of my application Serial Number 865,268, filed October 6th, 1914 for pneumatic tires.

This invention relates to a valve which is essentially adapted for use with a plurality of pneumatic tubes, the tubes being provided with means for inflating one or any number of the tubes.

The invention comprehends a valve formed of a plurality of segmental tubes, each tube being separable so that when one of the pneumatic tubes connected to the segments is punctured that particular tube can be removed from the casing to facilitate patching of the tube.

The fundamental object of the invention is to provide the segmental air inlet tubes with a removable device to lock them in assembled relation.

It also includes means coacting with the locking arrangement for firmly fastening the plurality of segmental tubes to the wheel rim.

The novel features of the invention are more fully described in the following specification and claims and illustrated in the accompanying drawings in which:

Figure 1 represents a vertical transverse section of a tire embodying this invention. Fig. 2 is a side elevation of the segmental air inlet tubes. Fig. 3 is a vertical section of one of the segmental air tubes. Fig. 4 is a horizontal section taken along the line $\alpha\alpha$ of Fig. 2.

In this drawing the letter a designates a rim which is of the ordinary clincher type and is provided with a felly a' to which the rim is clamped in the usual manner. An outer slotted tubular casing b is normally clinched to the rim as is well known. This casing is provided with a pair of partitions or annular diaphragms c projecting from the inner portion of the thread toward the rim portion of the casing. These partitions divide the inner portion of the casing into three chambers d each being open adjacent to the rim to give access to a chamber, and a

pneumatic elastic tube e is arranged in each chamber.

Connected to each pneumatic tube is an air inlet tube f extending outwardly through the slotted casing and a hole in the rim of the wheel. Each air inlet tube represents a divisional medium communicating with a pneumatic tube for pumping air into one or all of the tubes. Each segmental tube is exteriorly screw threaded as shown at g and the adjacent portions of the tubes are angular as indicated in Fig. 4 in order to bunch or nest the tubes together to form a cylinder with a number of bores. The outer ends of the tubes can be covered by means of a screw cap h to prevent dirt from entering or leakage of the air, and the end of each tube may also be separately covered or sealed by a screw cap o fitted to the upper part of the tube.

Coacting with the lower portions of the air segments is an adjustable sleeve i provided with interior threads for engagement with the threads of the segments. In this construction the sleeve will lock or firmly hold the tubes together in assembled formation before the valve is connected to the wheel rim. The lower portion of the sleeve has a flange j for coaction with the inner walls of the casing adjacent to the slit. The sleeve also has exterior threads for engagement with a nut k , best seen in Fig. 1. The nut when in place will jam against the wheel rim and force the flange j onto the walls of the casing thus clamping or locking the sleeve with the segments securely to the wheel rim. The stem of the valve when in place projects through a hole in the felly and the threaded stems of the segments where they issue from the felly are engaged by a nut m for alining and preventing lateral displacement of the segments relative to the felly.

Any form of spring air inlet valve p may be mounted in the bore of each tube to prevent the air from escaping from the tube. The air tubes can all be simultaneously inflated from a single pump so that the pressure in one air tube will equal the pressure in the other thus giving uniform resistance to the sides as well as the tread of the tire. The segmental tubes when clustered and locked together constitute practically a single inlet tube thereby facilitating the connection of a coupling when inflating the

tire. Sometimes it is desirable when one of the pneumatic tubes is punctured to increase the pressure in the other tubes, this function can be accomplished by capping 5 one or more of the air inlet tubes.

As indicated in the drawing the segmental tubes have their inner ends extending below the sleeve and two of the segments are positioned laterally to point in 10 opposite directions from the straight end of the other tube.

It will be readily understood that when 15 it is desired to repair a puncture in any of the pneumatic tubes, it will be necessary to loosen the nut *m* and slide the rim with the segmental tubes through a slot formed in the felly communicating with the hole.

In some wheel structures the rim is immovable relative to the felly, and in a construction 20 of this kind the nut *k* can be omitted. In this example the slotted casing *b* can be removed from the rim by removing the cap *h* and nut *m*, unclenching the casing, then drawing the segmental tubes through 25 the hole in the felly and rim.

I claim:—

1. A valve for pneumatic tires comprising 30 a plurality of segmental separable air inlet tubes normally clustered together, and a removable sleeve mounted on the tubes for locking the segments together.

2. A valve for pneumatic tires comprising 35 a plurality of segmental separable air inlet tubes normally abutting against each other to form a cylinder, and a removable sleeve adjustably engaging the cylinder for locking the segments together.

3. A valve for pneumatic tires comprising 40 a plurality of segmental threaded separable air inlet tubes normally clustered together, and a sleeve having interior threads for engagement with the threads of the tubes.

4. A valve for pneumatic tires comprising 45 a plurality of segmental threaded separable air inlet tubes normally clustered together, a sleeve having interior threads for

engagement with the threads of the tubes, and means coacting with the sleeve for locking it to the wheel rim. 50

5. A valve for pneumatic tires comprising a plurality of segmental separable air inlet tubes normally fastened together each having a lower extension one projecting radially and the others laterally in opposite 55 directions, a sleeve having interior threads for engagement with the threads of the tubes, and means engaging the sleeve for locking it to the wheel rim.

6. A valve for pneumatic tires comprising 60 a plurality of separable segmental threaded air inlet tubes normally clustered together, a sleeve having interior and exterior threads, the former threads being for engagement with the threads of the tubes, 65 and a nut made to engage the latter threads for locking the sleeve to a wheel rim.

7. In a valve for pneumatic tires the combination with a rim having a casing provided with a plurality of pneumatic tubes, 70 of a segmental threaded air inlet tube connected to each pneumatic tube extending through the rim and casing, a threaded sleeve to engage the threads of the segmental tubes, a nut to engage the sleeve 75 and lock it to the rim.

8. In a valve for pneumatic tires the combination with a rim having a casing provided with a plurality of pneumatic tubes, 80 of a segmental threaded air inlet tube connected to each pneumatic tube extending through the rim and casing, a threaded flanged sleeve to engage the threads of the segmental tubes, a nut to engage the sleeve and force the flange against the inner wall 85 of the casing.

In testimony whereof I have hereunto set my hand in the presence of two subscribing witnesses.

OTTO SCHUTZ.
